UNITED STATES PATENT OFFICE.

GEORGE LEAKE, OF MASON CITY, IOWA.

PHONOGRAPH-RECORD.

Specification of Letters Patent.

Patented May 6, 1919.

1,303,074.

Application filed July 31, 1918. Serial No. 247,573.

To all whom it may concern:

Be it known that I, GEORGE LEAKE, a citizen of the United States, residing at Mason City, in the county of Cerro Gordo and State 5 of Iowa, have invented a new and useful Phonograph-Record, of which the following is a specification.

The device forming the subject matter of this application is a record for a phonograph and the invention aims to provide a structure of the kind mentioned which may be played continuously, by reversing the direction of rotation of the record.

It is within the province of the disclosure 15 to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes in 25 the precise embodiment of the invention shown can be made without departing from the spirit of the invention.

In the accompanying drawings:—

Figure 1 is a top plan showing one form 30 of record constructed in accordance with the invention; Fig. 2 is a fragmental section taken longitudinally of one of the grooves; Fig. 3 is a perspective showing the projection or stop which operates the reversing mechanism; and Fig. 4 is a fragmental elevation showing a slight modification in the invention.

The numeral 1 marks a disk record having a sound groove 2 and a sound groove 3. 40 The sound groove 2 is extended at its outer end to form a terminal groove 4 connected with the groove 2 by a gradual slant as shown at 5, the terminal groove 4 being deeper than the grooves 2 and 3. The outer 45 end of the groove 3 is laterally extended as shown at 6 and opens as indicated at 7 into the terminal groove 4 above the bottom of the terminal groove. A cushion 8, made of rubber or like material, is mounted in the 50 terminal groove 4.

At its inner end, the sound groove 3 is extended to form a terminal groove 9 in which is located a cushion 10, the inner end of the groove 2 being laterally extended as shown 55 at 11, to communicate with the terminal groove 9, the construction being a duplicate

of that hereinbefore described in detail, and shown in Fig. 2. A projection 12 is mounted on the record 1 at the side of the groove 4, a projection 14 being mounted on the record at the side of the groove 9. The projections may be variously constructed and be variously located, but preferably, are formed on plates 15, each plate having an elongated slot 16 adapted to receive a set 60 65 screw 17 engaging the record 1, so that the projection may be adjusted longitudinally of the terminal groove.

In practical operation, the needle traverses the sound groove 2 to the inner end 70 thereof and then moves along the lateral extension 11 of the groove 12 into the groove 9. The projection 14 reverses the drive in the phonograph, and the needle starts back along the groove 3, the grooves 75 3 and 2 being oppositely recorded. The needle traverses the part 6 of the groove 3 and moves into the groove 4. The projection 12 effects a reversal in the direction 80 of rotation of the record, and the needle then traverses the groove 2, the operation above described being repeated as long as desired. Thus, it will be seen that a selection may be played indefinitely.

Because the extension 6 of the groove 3 85 opens into the groove 4 above the bottom of the said groove as shown at 7 in Fig. 2, the needle, having entered the groove 4 by way of the part 6 of the groove 3, will not move backwardly along the part 6 of the groove 90 3 when the direction of rotation of the record is reversed, but will move up the slant surface 5 into the groove 2. This operation will be carried out at the inner ends of the grooves 2 and 3, the needle 95 entering the groove 9 by way of the part 11 of the groove 2 and then traversing the groove 3 when the direction of rotation of the record is reversed.

The projections 12 and 14 are adjustable 100 longitudinally of the respective grooves 4 and 9 in order that they may coöperate properly with the phonograph mechanism, and, especially, in order that the pause which arises when the needle is traversing 105 the groove 4 or the groove 9 may be of the desired length, depending upon the time value of the rest which occurs in the music at the time the reversal takes place.

The resilient cushions 8 and 10 prevent 110 a jar and an injury to the needle or to the record when the needle enters the terminal

grooves, Fig. 2 being noted particularly at this point. It is not necessary that the invention be embodied in a disk record. In Fig. 4, a portion of a cylinder record 18 is shown, wherein the invention is embodied, parts hereinbefore described being designated by numerals previously used, with the suffix "a".

Having thus described the invention, what is claimed is:—

1. A phonograph record provided with oppositely recorded sound grooves which communicate at one end.
2. A phonograph record provided with oppositely recorded sound grooves which communicate at both ends.
3. A phonograph record provided with oppositely recorded sound grooves which communicate at one end; and a reversing projection on the record at the communicating end of the grooves.
4. A phonograph record provided with oppositely recorded sound grooves which communicate at one end; a reversing projection on the record at the communicating end of the grooves; and means for adjusting the projection longitudinally of the grooves.
5. A phonograph record provided with oppositely recorded sound grooves which communicate at both ends; and reversing

projections on the record at the communicating ends of the grooves.

6. A phonograph record provided with oppositely recorded sound grooves which communicate at both ends; reversing projections on the record at the communicating ends of the grooves and means for adjusting the projections longitudinally of the grooves.

7. A phonograph record provided with oppositely recorded sound grooves, one sound groove being extended to form a terminal groove, and the other sound groove opening into the terminal groove at a point above the bottom of the terminal groove.

8. A phonograph record provided with oppositely recorded sound grooves, one sound groove being extended to form a terminal groove, and the other sound groove opening into the terminal groove at a point above the bottom of the terminal groove; and a resilient cushion in the terminal groove.

In testimony that I claim the foregoing as my own, I have hereto affixed my signature in the presence of two witnesses.

GEORGE LEAKE.
